ATTORNEYS.

UNITED STATES PATENT OFFICE.

JOHN L. GIESSLER, OF CLINTON, IOWA.

IMPROVEMENT IN VEHICLE-SEATS.

Specification forming part of Letters Patent No. **155,299**, dated September 22, 1874; application filed August 26, 1874.

To all whom it may concern:

Be it known that I, JOHN L. GIESSLER, of the city and county of Clinton, and State of Iowa, have invented a new and Improved Spring Back-Rest for Vehicle-Seats; and I do hereby declare that the following is a full, clear, and exact description of the same, reference being had to the accompanying drawing forming a part of this specification, in which—

Figure 1 is a plan, and Fig. 2 a vertical section.

The invention relates to novel means whereby the jar, shock, or jolt to the back of an individual, resulting from the sudden starts of horses in a vehicle, or from unevenness in the roads, may be completely taken up and neutralized.

The invention consists in providing the seat of a vehicle with a pivoted back and spring-arms, as hereinafter fully described, and subsequently pointed out in the claim.

A represents the seat of a vehicle; B, the back; and C C, the arms. The back B is supported by two uprights, b b, which are of any suitable construction, and pivoted at b' b',

while the arms C C have ends bent, and projecting back within cavities covered by the slotted plates a a. The ends of arms C are each held forward in the front of slot by a spring, D, whose tension enables the back B to yield whenever force is applied thereto, or the weight of a person thrown against it.

This may be applied to old or new seats with but little expense, is thoroughly effective for the purpose intended, and will obviate a difficulty long felt and appreciated, but not hitherto sought to be remedied.

I am aware that there has been heretofore used a "lazy-back," attached to frame by hinges, while a pair of springs at the sides of seat serve as an arm-rest and to support the back; but

What I claim is—

The combination, with a vehicle-seat, of a hinged back and arms, C C, held forward by springs, in the manner and for the purpose specified.

JOHN L. GIESSLER.
